CLAIM

The ornamental design for a handheld shower nozzle, as shown and described.

DESCRIPTION

FIG. 1 is an elevated front perspective view of a handheld shower nozzle in accordance with the present design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings as shown in FIGS. 1-7 are directed to portions of the handheld shower nozzle that are not considered part of the claimed ornamental design.

1 Claim, 7 Drawing Sheets
